UNITED STATES PATENT OFFICE.

EDWIN CORCORAN, OF PORTLAND, OREGON.

STOVEPIPE LOCK.

Application filed August 30, 1927. Serial No. 216,445.

This invention relates to improvements in stove pipes, and has for its object to provide means whereby the pipe may be locked in place in the chimney.

5 Another object of the invention is to provide an attachment for a stove pipe whereby the same may be securely locked in the chimney.

With the above and such other objects in view as may hereinafter more fully appear, 10 I have invented the device illustrated in the accompanying drawings, in which:

Figure 1 is a sectional elevational view of a chimney showing a stove pipe locked 15 thereto;

Figure 2 is a sectional elevational view of a stove pipe embracing my invention;

Figure 3 is a view similar to Figure 1, showing the pipe unlocked for removal;

20 Figure 4 is a section on line 4—4 of Figure 1;

Figure 5 is a perspective view of my locking device, detached from the stove pipe; and

25 Figure 6 is a section on line 6—6 of Figure 1.

Like reference characters indicate like parts throughout the specification and in the several views in the drawings, in which 1 indicates a chimney having a pipe opening 2, through which one end 3 of a stove pipe 4 is adapted to project. My invention consists of the attachment 5 illustrated in Figure 5, and which consists of a pair of spaced apart ring bands 6 and 7 connected together by arms 8, the said rings snugly fitting against the inner wall 9 of said pipe 4, ring 6 having its outer edge 10 projecting very slightly beyond the edge 11 of the pipe 4 and the inner 35 ring 7 is provided with a beveled outer wall surface 12 the knife edge 13 thereof projecting inwardly of said pipe. On the outside of said pipe 4 is provided another wedge shaped ring 14 its knife edge 15 projecting in the direction of the chimney 1 and being forced directly over the ring 7 whereby the 40 wall 16 of the pipe 4 will be tightly wedged between said rings and distorted thereby, negating the possibility of said rings becoming 45 loosened and unseated relative to one another. The ring 14 is provided with opposing ears 17 and 18 having apertures 19 and 20 through which wires 21 and 22 pro-

ject, these wires provided with heads 23, whereby the wires are manipulated; said 55 wires 21 and 22 projecting over the pipe 4 through opening 2 and having the inner terminals linked to the edges 23 and 24 of the lock members 25 and 26 hinged at 27 and 28 to the said projecting edge 10 of ring 6 60 in order that when said heads 23 are pulled upon drawing out the wires 21 and 22 the members 25 and 26 are operated to vertical position and engage the inner wall 29 of the chimney 1. Clamps 30 and 31 are provided 65 on the outer ends of wires 21 and 22 whereby they may be held in the outermost position to lock the members 25 and 26 in the vertical position whereby it will be impossible 70 for the pipe 4 to become accidentally detached from its chimney 1. As the ring 14 seats directly the pipe collar 32 the same will be held in place against the wall 33.

Having described my invention, that which I claim to be new, and desire to procure by Letters Patent, is:

1. In combination with a stove pipe, lock members, means in said pipe for carrying said members, said means consisting of a band ring held in said pipe and another ring clamped in the pipe to which the band ring is linked.

2. In combination with a stove pipe, lock members, means in said pipe for carrying said members, said means consisting of a band ring held in said pipe, another ring clamped in the pipe to which the band ring is linked, and an outer ring on said pipe for clamping the pipe to the first clamp ring.

3. In combination with a stove pipe, lock members, means in said pipe for carrying said members, said means consisting of a band ring held in said pipe, another ring clamped in the pipe to which the band ring is linked, an outer ring on said pipe for clamping the pipe to the first clamp ring, and means connected to said outer ring for manipulating said lock members.

4. The combination set forth in claim 3, said means consisting of wires linked to said members.

5. The combination set forth in claim 3 said means consisting of wires linked to said lock members, and brackets carried by said last ring through which said wires project.

105 6. The combination set forth in claim 3,

said means consisting of wires linked to said lock members, brackets carried by said last ring through which said wires project, and means for securing said wires in fixed position.

6. 7. In combination with a stove pipe, lock members, means in said pipe for carrying

said members, said means consisting of a band ring held in said pipe and another ring clamped in the pipe to which the band ring is linked, said lock members being hingedly connected to said band ring. 10

In testimony whereof I affix my signature.

EDWIN CORCORAN.
